CORRECTIVE BRASSIÈRE

Patricia Clancy, San Diego, Calif.

Application March 18, 1933. Serial No. 661,546

3 Claims. (Cl. 2—42)

REISSUED

This invention relates to garments of the brassière type and particularly to a brassière garment having for one of its principal objects the provision of improved means for corrective rejuvenating, invigorating and restoring in a superior manner the broken down tissues of a woman's bust, whereby drooping breast are caused to resume a more upright position, hence contributing to a woman's figure, 10 comfort and health.

It is an object of the invention to provide an improved combination of parts for a garment of this kind which may be united to each other in such a manner that the garment as a whole 15 will be comfortable, durable and will dependably maintain itself in the proper wearing position.

A particular object of the invention is to provide a superior reinforced forwardly expanded 20 portion of the garment which will fit over each breast in a more perfect manner and which may be depended upon to hold up and slightly compress the breast in the manner which is most conducive to health and to improvement of the figure.

Still another object of the invention is to provide means to support the brassière from the shoulders of the wearer in a more dependable, comfortable and hygienic manner, and in such a 30 manner that it may be held up at higher levels as the process of rejuvenation proceeds.

Other objects, advantages and features of the invention may hereinafter appear.

Referring to the accompanying drawings which 35 illustrate what is at present deemed to be a preferred embodiment of the invention,

Fig. 1 is a front elevation of the complete article, except that a portion of one of the shoulder straps and back straps is broken away.

Fig. 2 is a back view of the article, certain 40 terminal portions being broken away to contract the view.

Fig. 3 is a vertical section taken through the mid-width of the left hand shoulder strap of 45 Fig. 1.

Fig. 4 is a plan view of the assembly of fabric blanks of which the article is composed, these blanks being shown juxtaposed to each other in such a manner as to indicate the proper manner 50 of assembling them. Parts of the longest blanks are broken away to contract the view.

Fig. 5 is a plan view, on a reduced scale, completely showing one of the companion blanks which are broken away in Fig. 4. These pieces 55 are related to an important feature of the invention.

Referring in detail to the drawings, a description will be given of the right hand half of the article, it being understood that the two halves 60 thereof are duplicates. The outer side sections

5 are of a somewhat wedged shaped character. Their tapered ends are directed rearwardly and have the tie strips 5a secured to them. Each of these side sections is provided at its wide end with an upper edge 6 which is slightly curved 65 in an outward manner, and with a straight lower edge 7 which joins said edge 6 in such a manner as to form an outwardly directed angle. To the front end of each member 5 is stitched the double breast member 8, 8', shown in section in Fig. 70 3. Said breast member consists of two superposed members having triangular base portions, the apex of their triangles being continued upwardly into extensions 9, 9'. The innermost of these superposed members has a relatively short 75 extension 9' as seen in Fig. 2, but the outer breast member has its extension 9 continued upwardly, backwardly and downwardly to form the shoulder strip 10. The back end of this shoulder strip is stitched to the rear portion of the side 80 piece 5. The fabric piece for each shoulder strip is considerably wider than the completed strip, and the side portions thereof are folded downwardly to meet at the mid-width of the strip, where they are stitched thereto.

The members 5a are of such elasticity or stretchability that they may be elongated or stretched several times their normal length so as to oppositely semi-encircle the body and be fastened together directly in front of the body 90 subjacent the mid-center of the device as indicated in the lower portion of Fig. 1.

This construction enables a saggy breast to be raised or cultivated back to its normal position by various or continuous elevating stages, that 95 is to say, the waist band of the brassière is elevated from one level to another as the broken down tissues are restored or are being built up. The brassière proper may be elevated to maintain the broken down tissues in their built up 100 condition and thus permit the building up of additional tissues to maintain the bust in a more elevated position until at last the bust is completely built up to its original position.

A heavy bust will require greater stress being placed in the elastic to maintain its fixed position than a light one and the adjustment from one point of elevation of the bust to another is varied slightly to conform to the comfort and wishes of the wearer.

The operation whereby this adjustment is regulatable consists in grasping the brassière at a point 9 by right hand on the left side and raising that point of the brassière together with the bust to a position it is desired to elevate the bust and then grasping the elastic strip 5a that continues from the right side by the left hand, pulling on said elastic until the desired comfortable or building up position is obtained. The elastic tie strips 5a are then secured together around 120

the body in a crosswise fashion to keep the brassière in the adjusted position. The looseness of the elastic is thereby converted from the rear to the front of the body.

5 The ends of the strip 5a are fastened together in front in any suitable manner as by the terminal catch elements 5b and 5c.

The member 10 is slightly curved and inclines toward the back center. The straps 10 are secured 10 to the terminal portion of the members 5 near the center of the back and being curved inwardly aid in preventing the straps from falling over the shoulders.

In Fig. 5 is shown in detail the novel form of the 15 blank for the combined breast piece and shoulder strip, the curvatures of the edges thereof being exaggerated for clearness of illustration. It will be seen that the edges of the extension 9 are substantially parallel and are both curved toward 20 one side, and the edges of the portion 10 are also substantially parallel, but are both curved in the reverse direction.

The front portion of the article is completed by the two companion sternum pieces 12 which are 25 each shaped as a semi-heart shaped body, as seen in Fig. 4. In stitching these members together, their meeting edge portions are each provided with a series of transverse tucks 13. Hence when the stitching is completed the meeting edges of 30 these pieces are shortened, thereby forming an upwardly and laterally extending wing 14 at each side of the median line. The superposed extensions 9, 9', as viewed from the front are each slightly curved with the convex side directed 35 toward the center. This construction forms a more natural support for each breast and also causes the strain upon the shoulder strip to be directed inwardly as well as downwardly overcoming the tendency of the strap to slip off from 40 the shoulder. Moreover, the shoulder strip thus provided will engage the tissues of the shoulder in a squarely flat-wise manner and will therefore not leave a red mark upon the skin or in any-wise irritate this part of the body.

45 Both the side edge portions of the superposed breast pieces 8 are lapped over and are stitched to the adjoining edge portions of the fabric. The sectional view (Fig. 3) illustrates this feature. Also the base edges of the superposed triangular portion 8, 8' are included within an edge fold 20x with which the part 20 is provided as 50 shown in Fig. 3.

Along the inner side of the lower portion of the article a combined reinforcing member and 55 breast pocket member 20 is provided, said member consisting of an elongated strip having a straight lower edge and tapered end portions 21. The upper edge 22 of each end portion 21 is

straight and downwardly inclined as best shown in Fig. 4. Said end edges 22 are connected by two concave edges 23 which meet at an upwardly directed angle 24 at the center of the piece. Opposite said angle 24, vertical stitching 25 secures the piece 20 to the front portion of the article, the pieces 12 meeting at this point and having their contiguous edges stitched down as well shown in Fig. 2.

No generic claim is made to the breast or back pocket feature per se, but one of the novel features of the invention pertains to the double breast strip 8 which is located at the mid-width of each breast pocket, and which is suited not only to conform to the natural shape of the breast but also, in combination with the shoulder strip, to sustain the breast-supporting part in a more dependable manner.

The various edge portions of the article are provided with suitable bindings, as shown.

I claim:

1. In a brassière, a structure consisting of two complementary halves each of which has a breast pocket construction which includes a front side breast member, the latter consisting of two superposed similar fabric pieces having downwardly diverging side edges; a sternum piece stitched to the inner side edges of said breast member; an outer side piece stitched to its outer side; and means to complete the entire structure, said 105 means including shoulder strips continuous with the upper portions of said superposed pieces.

2. In a brassière, a body-encircling structure which is made up in part of a breast member having downwardly diverging side edges, said 110 breast member being a sheet of fabric a portion of which is narrowed and extended upwardly to perform the function of a shoulder strap, said upwardly extended portion being curved laterally away from the median line in order to cause the 115 shoulder strap portion thereof to engage the shoulder in a flat-wise manner.

3. In a brassière, a heart-shaped sternum piece consisting of two complementary halves which are stitched together at the median line, transversely extending tucks being provided in each half of said sternum piece, said tucks extending outwardly from the median line, a breast piece consisting of a piece of fabric stitched to each of the outer edges of said sternum piece, the 125 lower part of said breast piece having downwardly diverging side edges and the upper part of said breast piece being continued upwardly to perform the function of a shoulder strap, and means secured to the outer edges of said breast 130 pieces to extend the article around the body of the wearer.

PATRICIA CLANCY.
